United States Patent Office

Des. 174,881
Patented May 31, 1955

174,881

MANNEQUIN OR SIMILAR ARTICLE

Frank Whitton Lamborn, Philadelphia, Pa.

Application July 1, 1952, Serial No. 20,430

Term of patent 14 years

(Cl. D34—4)

Fig. 2.

To all whom it may concern:

Be it known that I, Frank Whitton Lamborn, a citizen of the United States, residing at Philadelphia, in the county of Philadelphia, State of Pennsylvania, have invented a new, original, and ornamental Design for a Mannequin or Similar Article, of which the following is a specification, reference being had to the accompanying drawings, forming part hereof.

The rear view of the mannequin or similar article is substantially similar to that shown in the front view of Figure 1.

I claim:

The ornamental design for a mannequin or similar article, substantially as shown.
